UNITED STATES PATENT OFFICE.

AUGUST H. FLECK, OF OKLAHOMA, OKLAHOMA.

SURGICAL DEVICE.

1,334,237.

Specification of Letters Patent. Patented Mar. 16, 1920.

Application filed January 7, 1919. Serial No. 270,018.

To all whom it may concern:

Be it known that I, AUGUST H. FLECK, a citizen of the United States of America, residing at Oklahoma, in the county of Oklahoma and State of Oklahoma, have invented new and useful Improvements in Surgical Devices, of which the following is a specification.

This invention has reference generally to improvements in that class of inventions known as surgery and more particularly has reference to a surgical device.

It is the principal aim and object of this invention to provide a device of the above mentioned character designed to be inserted in the vagina and inflated for holding a saturated absorbent member in the proper position, thus serving as an effective treatment for social diseases and at the same time acting to properly support the womb.

More particularly this invention consists in the provision of a device of the above mentioned character wherein there is employed a pneumatic cushion and an absorbent mantle arranged in surrounding relation and supported by the cushion when the latter is inflated, thus insuring of the healing and disinfecting solution, with which the mantle is either saturated or coated, coming in contact with the affected parts for the curing of the same.

It is a more specific object of this invention to provide a device of the above mentioned character wherein a speculum and rod are employed for use in conjunction with the cushion and mantle for the proper positioning of the latter and to also provide means for inflating the cushion subsequent to the application thereof.

Among the other aims and objects of this invention may be recited the provision of a device of the character described with a view to compactness, and in which the parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connec-

tion that minor changes in the construction and arrangement of parts may be made without departing from the principle of operation of the various parts. 60

The invention is clearly illustrated in the accompanying drawings, in which:—

Figure 1 is a side elevation showing the device applied.

Fig. 2 is a longitudinal sectional detail of 65 the various parts assembled preparatory to being applied.

Fig. 3 is an enlarged longitudinal sec- 70

Fig. 4 is a sectional detail of the inflat- 75

ing bulb.

Fig. 5 is a detail perspective view of one

end of the pneumatic cushion.

Similar characters of reference are em- 75

ployed in all of the above described views

to indicate corresponding parts.

Referring now, more particularly to the accompanying drawings there is provided a tube 1, hollow and either round or oval in cross section as described, both ends being 80 open while one end in addition is flared as at 2. This tube is designed to facilitate the application of the device, it being formed of suitable metal and of course is removed when the device is ready for use as will be- 85

come apparent.

A pneumatic cushion 3 is employed and is preferably of an elongated form, the end 4 being formed with an opening 16 back of which there is fitted a check valve 5. 90

Arranged in surrounding relation with the cushion 3 is a similarly shaped mantle 6 of cloth or absorbent material. One end of the mantle is closed while the other end is open forming in effect a bag. 95

In assembling the parts the bag-like mantle is arranged in surrounding relation with the cushion while both the mantle and cushion are arranged within the tube, the latter being in contact with the mantle. 100

In applying the device in position a sec- 105
tional rod 7 is provided and is composed of two sections 8 and 9. The solid section 8 is telescoped within the hollow section 9 while the latter is formed with an elongated bayonet slot 10 in which is engaged a lug 11, formed with the solid section 8, by this construction these sections may be releas- 110
ably locked in an extended position. The rod is arranged between the cushion and the mantle, one end abutting the closed end of the latter while the tube is forced into the

vagina, subsequent, of course, to the saturating of the mantle with a disinfecting and healing solution. The tube is now withdrawn, the knot 12 on the handle being held 5 to prevent the withdrawal of the cushion and mantle.

A rubber bulb 13 having a hollow stem 14 is used for inflating the cushion, the stem being inserted in the opening 16, such 10 inward movement being limited by lugs 15 on the stem which lugs pass through slots 17 formed on diametrically opposite sides of the opening 16. When the cushion is inflated the stem is removed, the valve 5 15 serving to hold the cushion in an inflated condition while the cushion in turn yieldingly supports or holds the saturated or coated mantle in engagement or contact with the affected parts for the effective cur- 20 ing thereof. When it is desired to remove the cushion and mantle it is only necessary to insert the stem of the bulb 13 in the opening 4 to open the valve 5 and release the air and thus deflate the cushion, thereby 25 permitting of an easy removal of the cushion and mantle.

It is believed in view of the foregoing description that a further detailed description of the device is entirely unnecessary. 30 Likewise it is believed that the advantage of the invention will be readily apparent.

The invention having been described, what is claimed as new and useful is:—

1. A device of the character described including a pneumatic cushion and an absorbent mantle arranged in surrounding relation therewith and supported thereby. 35

2. A device of the character described including a pneumatic cushion, an absorbent mantle disposed thereabout, and a tube disposed about the mantle and cushion to facilitate the application thereof and being subsequently removable. 40

3. In a device of the character described in combination, a pneumatic cushion, hav- 45 ing an opening in one end, a valve for closing the opening, a bag-like absorbent mantle arranged in surrounding relation with respect to the cushion, means for facilitating the application of the cushion and mantle, 50 means for facilitating the removal of the first mentioned means without disturbing the cushion and mantle, and means for inflating the cushion.

4. A device of the character described comprising a tubular absorbent mantle, and means for inserting it in an affected part of the human body in a collapsed condition and subsequently extending it for intimate contact with such affected parts. 55

In testimony whereof I affix my signature. 60
AUGUST H. FLECK.
